PORTABLE MANUALLY OPERATED RUG SHAMPOOER

Howard A. Anderson, Pittsburgh, Pa., assignor to Bissell Inc., Grand Rapids, Mich., a corporation of Michigan

Filed Aug. 24, 1966, Ser. No. 3,575

Term of patent 14 years

(Cl. D9—2)

Fig. 1.

Fig. 5.

Fig. 2.

Fig. 3.

Fig. 4.

Fig. 6.

FIG. 2 is a side elevation thereof, the side opposite being a mirror image;

FIG. 3 is a top plan view thereof;

FIG. 4 is a bottom plan view thereof;

FIG. 5 is a front end elevation thereof; and

FIG. 6 is a rear end elevation thereof.

I claim:

The ornamental design for a portable manually operated rug shampooer, substantially as shown and described.
